UNITED STATES PATENT OFFICE.

ARTHUR B. ELLERY, OF AKRON, OHIO.

TRIPPING MECHANISM FOR PRINTING-PRESSES.

1,076,965.

Specification of Letters Patent.

Patented Oct. 28, 1913.

Application filed January 27, 1913. Serial No. 744,414.

To all whom it may concern:

Be it known that I, ARTHUR B. ELLERY, a citizen of the United States, residing at Akron, in the county of Summit and State of Ohio, have invented a new and useful Tripping Mechanism for Printing-Presses, of which the following is a specification.

My invention relates to tripping mechanism for printing presses and more especially to the tripping mechanism used upon the double cylinder or two-color type of press.

Heretofore great difficulty has been experienced by the operator of this type of press in tripping each of the cylinders at exactly the proper time, it being necessary that the several parts of the press be in exactly the proper relation to each other at the moment each cylinder is tripped. At the present time it is necessary for the operator to trip the first cylinder when it is in the sheet receiving position and then to manually trip the second cylinder at a fixed or stated definite time after the first cylinder has been tripped, or rather at a time when the second cylinder has reached a certain specific position. Even the most expert operators encounter a great deal of difficulty in timing the tripping of the second cylinder accurately and properly and are to a great extent handicapped in their work on this account. With the present form of tripping mechanism more or less time and material is wasted by the second cylinder being tripped at the wrong time, some times two or three sheets being spoiled successively owing to the second cylinder being tripped a moment too soon or too late.

The fundamental object of my invention is to provide a tripping mechanism for a double cylinder press, which will automatically trip the second cylinder at a definite predetermined time after the tripping of the first cylinder.

A further object is to provide a tripping mechanism by which either of the cylinders may be tripped independently of the other or which may be actuated simultaneously to trip the first cylinder immediately and the second cylinder at a predetermined definite time afterward.

These objects, together with other objects readily apparent to those skilled in the art, I attain by the construction illustrated in the accompanying drawings, although my invention may be embodied in a variety of

other mechanical forms, the construction illustrated being chosen by way of example.

In the accompanying drawings: Figure 1 is a side elevation of a portion of a multi-cylinder press provided with my improved tripping mechanism, the relative parts shown in the positions in which they would appear when the trip pedals are depressed in order to trip the cylinders successively, at 60 the time when the first cylinder is in the position to receive a sheet. Fig. 2 is a fragmentary elevation of the lower portion of the press showing the tripping mechanism in the normal position. Fig. 3 is a bottom 70 plan view of a portion of the tripping mechanism in the position shown in Fig. 1. Fig. 4 is a detached perspective view showing the inner face of the cam which actuates the rock arm and tripping mechanism which 75 trips the second cylinder. Fig. 5 is a perspective view of a portion of the rock arm and the tripping mechanism which actuates said rock arm.

Similar numerals of reference indicate corresponding parts throughout the several views.

The press illustrated in the accompanying drawings is of a type well known to those skilled in the art, showing a press provided with a reciprocating bed-plate and a pair of imprinting cylinders located above said bed and adapted to be raised and lowered with relation to said bed, and a conveying cylinder located between said printing 85 cylinders and adapted to convey the printed sheet, after it has received the impression from the first cylinder, to the second cylinder where it receives the second impression. Presses of this character are in common use 95 wherever two-color printing is done and are familiar to, and well understood by, those versed in the art of printing so that it is not thought necessary to go into great detail in the description of the press itself, it only 100 being necessary to locate the various members of the press with relation to my improved tripping mechanism.

Referring to the accompanying drawings and more specifically to Figs. 1 and 2 the 105 numeral 1 indicates the side frame of a printing press of the type referred to, provided with a horizontally reciprocating bed-plate 2. The first and second printing cylinders 3 and 4 respectively 110 are each provided with the journals 5, which are mounted in the journal boxes

6, said journal boxes being slidably mounted in the guides 7 located in suitable uprights 8 upon the frame of the press. A conveying cylinder 9 is located between the 5 imprinting cylinders 3 and 4 and adapted to carry the sheet from the cylinder 3 after it has received the first color and transfer it to the cylinder 4 at the proper time to receive the second color or impression. In 10 presses of this type the imprinting cylinders are adapted to be raised and lowered with relation to the bed-plate of the press. In the press illustrated the imprinting cylinders are normally held in a raised position 15 by the expansion springs 10, this being the usual construction. Presses of this character are usually provided with a series of links and cams or other positively operating mechanism for lowering the cylinders. In 20 the machine upon which I have chosen to illustrate my tripping mechanism each cylinder is provided with an eccentric 11, to which is rigidly attached a pair of rock arms 12, (only one of which is shown upon 25 each cylinder in the drawings), one of said rock arms being provided at either end of the cylinder. Downwardly depending from the free end of each rock arm 12 is a pivotally connected link 13, the lower extremity 30 of each link being pivotally connected to a rock arm 14, each of said rock arms being rigidly connected to a rock shaft 15. Each of the rock shafts 15 is rocked by means of a suitable cam, not shown, upon the rear 35 side of the press. It is not thought necessary to go into detail as to the construction of this cam as this is a construction common to all presses of this type and needs no further description, it only being necessary 40 that some such mechanism is employed to rock the shafts 15 properly.

The rock shafts 16 and 16^a are provided upon their rear ends with the ordinary tripping mechanism such as is common in 45 presses of this character, which mechanism is adapted to trip the cylinders 3 and 4 respectively. The rock shaft 16 is provided upon its forward extremity with the rigidly connected lever 17 provided with the pivotally connected foot pedal 18 and held in 50 raised position by means of the expansion spring 19. It will be readily seen that by depressing the pedal 18 the rock shaft 16 will be rocked through the medium of the lever 17 and the tripping mechanism of the ordinary construction heretofore mentioned will be operated, thereby tripping the first 55 cylinder 3. Pivoted upon the shaft 16 is the bell crank having the long and substantially horizontal arm 20, and the comparatively short vertical arm 21. The arm 20 is provided with a foot pedal 22, and is held in raised position by a spring 23 similar to the spring 19 on the lever 17. The short 60 arm 21 of the bell crank is provided with 65

the horizontally disposed, flexible rod 24, the free end of which contacts with the angular lever 25, which is pivotally connected as at 26 to a suitable bracket 27 secured upon the frame 1.

The lever 25 ordinarily rests upon the stop 27, provided upon the forward face of the bracket 27, which holds the lever normally out of contact with the rod 24. The upright arm 28 of the lever 25 is adapted 70 to be brought into contact with the rear end of the stud 29, which is slidably mounted within an aperture 30 located in the free end of the bent rock arm 31 and provided upon its forward end with an anti-friction 75 roller 32. The rock arm 31 is rigidly secured to the rock shaft 16 which as has been heretofore mentioned is provided upon its rear end with the ordinary tripping 80 mechanism such as is common in presses of 85 this type, and is for the purposes of tripping the second imprinting cylinder 4. The cam 33 is fixedly mounted upon the shaft 34 which is suitably rotated by a series of 90 gearing, not shown, which is located upon 95 the rear side of the press. It is not thought necessary to show up the gearing for rotating this cam or for that matter any of the 100 gearing which rotates the cylinders and operates the other parts of the press as this is all of common construction and is used upon all presses of this character and forms no specific part of this invention, other than that a driving means is of course necessary for the different parts of the press. The cam 33 is provided with the concentric portion 35 extending through substantially half of its circumference, and with the eccentric portion 36. An inclined projection 37 is located upon the cam adjacent the eccentric 105 portion 36. The lever 31 is held in its normal position by means of the expansion spring 38.

So much of the press is of the ordinary construction such as is in common use at the present time and the operation thereof is as follows. When it is desired to trip the first cylinder 3 pressure is manually exerted upon the pedal 18, which will rock the shaft 16 through the medium of the rock arm 17, and thereby cause the tripping mechanism for the cylinder 3 to be operated. Now if it is desired with this machine to trip the second cylinder the operator must judge the time exactly and after tripping the first cylinder 110 must manually depress the pedal 22, rocking the bell crank upon the shaft 16 and bringing the flexible rod 24 into contact with the angular lever 25. The operator may gage 115 the time and position of the cylinders as accurately as possible and then depress both of the pedals at once, but this requires very accurate judgment as to the exact instant when the pedals must be depressed and is very often unsuccessful. This action will 120 125 130

cause the vertical arm 28 of the lever to come in contact with the rear end of the stud 29 moving said stud forward against the face of the cam 33 and bringing the anti-friction roller 32 into engagement with the concentric portion 35 of the cam. As soon as the parts reach this position the operator may remove the pressure from the pedal 22, thereby, allowing the bell crank to resume its normal position as shown in Fig. 2 of the drawings; the flexible rod 24 dropping away from the angular lever 25, which allows said lever to resume the position shown in Fig. 5 of the drawings. The stud 29 however will remain in its forward position, the anti-friction roller 32 still being held in contact with the cam 33. As the cam revolves the eccentric portion 36 will travel over the roller 32 thereby rocking the arm 31, which in turn rocks the rock shaft 16 causing the tripping mechanism for the second cylinder 4 to be operated.

The greatest difficulty is found by the operator of the press in properly judging the time to depress the pedal 22 and much time and material is thus wasted. It is the purpose of my invention to entirely do away with this difficulty by connecting the trip operating mechanism of the second cylinder directly to the trip operating mechanism of the first cylinder so that by manually depressing the pedal which operates the tripping mechanism for the first cylinder the second cylinder will be automatically tripped at a predetermined definite time after the tripping of the first cylinder. For the purpose of thus coupling the tripping mechanism of the two cylinders I provide a link 39 pivoted at its lower end to the rock arm 17 and at its upper end to the substantially horizontal arm 40 of a bell crank pivoted at 41 to the frame 1 of the press, the substantially vertical arm 42 of the bell crank being pivotally connected to the hook 43, which engages the eye 44 upon the free end of the foot 45 of the link 46, which link is pivotally connected at its lower end to the set collar 47 secured upon the flexible rod 24 by means of the set screw 48. A thrust collar 49 is secured upon the link 13 of the first cylinder 3 by means of a set screw 50 and is adapted to engage the foot 45 of the link 46 as will be hereinafter described.

The operation of this device is as follows: When it is desired to trip the first and second cylinders it is only necessary to depress the pedal 18 which through the medium of the rock arm 17 will rock the shaft 16 and thus operate the tripping mechanism for the first cylinder 3. At the same time the link 39 will be drawn down by the downward movement of the arm 17 thus rocking the bell crank into the position shown in Fig. 1 of the drawings, the hook 43 being carried forward by this movement of the bell crank

and bringing the foot 45 of the link 46 into position to be engaged by the thrust collar 49 as shown in Fig. 1 of the drawings. The link 46 will thus be moved slightly in a vertical direction thus bringing the free end 70 of the flexible rod 24 into juxtaposition to the lever 25. Upward movement of the link 13 will bring the thrust collar 49 into contact with the foot 45 and thus raise the link 46 carrying with it the flexible rod 24. This 75 upward movement of the rod 24 will operate the angular lever 25 which in turn throws the anti-friction roller 32 into contact with the cam 33 as described and the rest of the operation is precisely the same as when the 80 pedal 22 is manually operated to trip the second cylinder.

By depressing both levers 18 and 22 at the same time as shown in Fig. 1 the same result may be obtained although it is unnecessary to depress the lever 22 at all. If it is desired to use the press without the automatic tripping device it may be easily detached by removing the hook 43 from the eye 44, or the set screw 50 in the thrust 90 collar 49 may be loosened enough to move said collar downward out of contact with the foot 45.

I claim—

1. In a multi-cylinder press of the character described provided with means for tripping the first cylinder, said means including a manually operated rock arm and a vertically reciprocating link and with means for tripping the second cylinder, said 95 means including a flexible rod, an attachment connecting said rock arm to said flexible rod and means upon said vertically reciprocating link for operating said attachment.

2. In a multi-cylinder press of the character described provided with means for manually tripping the first cylinder, said means including a manually operated rock arm and a vertically reciprocating link and with means for tripping the second cylinder, said means controlled by a flexible rod, flexible means connecting said flexible rod to said manually operated rock arm and a thrust collar carried by said vertically reciprocating link and adapted to contact with said flexible means.

3. In a multi-cylinder press of the character described provided with means for manually tripping the first cylinder, said 120 means including a manually operated rock arm and a vertically reciprocating link and with means for tripping the second cylinder, said means controlled by a flexible rod, means for coupling said flexible rod to said 125 manually operated rock arm, said means comprising a link pivotally connected to said flexible rod, a foot formed upon said link, a detachable link connected to said foot, a bell crank pivotally connected to said detachable 130

link, a third link connected to said bell crank and said manually operated rock arm and a thrust collar carried by said vertically reciprocating link and adapted to engage 5 said foot.

4. In a multi-cylinder press of the character described provided with means for tripping the first cylinder, said means including a manually operated rock arm and a 10 vertically reciprocating link and means for tripping the second cylinder, said means including a flexible rod, flexible means connecting said rock arm to said flexible rod and a thrust collar carried by said vertically reciprocating link and adapted to engage said 15 flexible means when said rock arm is manually operated automatically tripping said second cylinder at a predetermined definite time after the tripping of said first cylinder.

20 5. In a multi-cylinder press of the character described provided with means for tripping the first cylinder, said means including a manually operated rock arm and a vertically reciprocating link and means for 25 tripping the second cylinder, said means including a flexible rod; a link connected to said flexible rod, a foot formed upon said link, a detachable link connected to said foot, a bell crank pivotally connected to said de- 30 tachable link, a third link connecting said bell crank to said manually operated rock arm, and a thrust collar carried by said vertically reciprocating link and adapted to engage said foot when said rock arm is 35 manually depressed, causing said second cylinder to be tripped at a predetermined definite time after the tripping of the first cylinder.

6. In a multiple-cylinder press of the character described, provided with means for 40 tripping the first cylinder, said means including a manually operated rock arm and a vertically reciprocating link and means for tripping the second cylinder, said means

including a rod, means connecting said rock arm to said rod and a thrust collar carried by said vertically reciprocating link, and adapted to engage said means when said rock arm is manually operated automatically tripping said second cylinder at a predetermined time after the tripping of said first cylinder. 45 50

7. In a multi-cylinder press of the character described provided with means for tripping the first cylinder, said means including a manually operating rock arm and a vertically reciprocating link and means for tripping the second cylinder, said means including a rod, a link connected to said rod, a foot formed upon said link, a bell crank pivotally connected to said detachable link, a third link connecting said bell crank to said manually operated rock arm, and a thrust collar carried by said vertically reciprocating link and adapted to engage said foot when said rock arm is manually depressed, causing said second cylinder to be tripped at a predetermined definite time subsequent to the tripping of the first cylinder. 55 60 65 70

8. In a multi-cylinder press of the character described provided with means for tripping the first cylinder, said means including a manually operated rock arm and a vertically reciprocating link and means for tripping the second cylinder, said means including a rod, an attachment connecting said rock arm to said rod and means upon said vertically reciprocating link for operating said attachment. 75 80

In testimony that I claim the above, I have hereunto subscribed my name in the presence of two witnesses.

ARTHUR B. ELLERY.
